UNITED STATES PATENT OFFICE.

EDWARD A. CUNNINGHAM, OF PHILADELPHIA, PENNSYLVANIA.

CARBON-DIOXID GAGE.

1,119,666.

Specification of Letters Patent. Patented Sept. 22, 1914.

Application filed September 6, 1913. Serial No. 768,406.

To all whom it may concern:

Be it known that I, EDWARD A. CUNNINGHAM, a subject of the King of Great Britain residing at Philadelphia, in the county of Philadelphia and State of Pennsylvania, have invented a new and useful Carbon-Dioxid Gage, of which the following is a specification.

My invention relates to apparatus used in determining the percentage or proportion of carbon dioxid (CO_2) or similar gases and vapors contained in a mixture of gases such as the products of combustion passing into the stack flues or stacks of steam boilers, heating furnaces and similar devices, and the invention more particularly relates to a novel apparatus for gaging the carbon dioxid content (CO_2) of such gases and recording the fluctuations in the amount thereof in the mixture of gases.

One object of my invention is to provide a cheap and effective gaging mechanism having novel means whereby the carbon dioxid content of the waste gases passing into a stack flue or stack or similar mixtures of gases, is easily and quickly determined.

Another object of this invention is to provide a gaging mechanism of improved construction having novel means whereby the percentage of carbon dioxid contained in the waste gases passing into or through the smoke stack or stack flue, is determined while the necessity of measuring the volume of the mixture of gases is avoided and overcome.

A further object of the invention is to provide a carbon dioxid gage having means whereby the percentage or proportion of carbon dioxid contained in a column of waste gases is indicated and variations in the quantity of carbon dioxid are shown and recorded.

A still further object of my invention is to provide novel means whereby a signal is made when the percentage of carbon dioxid contained in the gases reaches a predetermined amount, and still further objects of my invention will become apparent as the apparatus is more fully disclosed hereinafter.

Referring to the drawings forming part of this specification, Figure 1 is a side elevation showing one form of carbon dioxid gage as constructed and arranged in accordance with my invention. Fig. 2 is a side

elevation, in a plane at right angles to the plane of Fig. 1, further illustrating the apparatus of Fig. 1. Fig. 3 is a detail longitudinal section, on a larger scale, showing the construction of the vessel or chamber containing the reagent employed and forming part of my improved apparatus. Fig. 4 is a section, in a plane at right angles to that of Fig. 3 on the line IV—IV of Fig. 3. Fig. 5 is a transverse section of the apparatus of Figs. 3 and 4, the section being taken on the line V—V of Fig. 3.

In the accompanying drawings the numeral 2 designates a tubular member arranged to form an absorption chamber in which the solid caustic potash or other reagent, or, when used, an absorbent material saturated with a suitable reagent, is placed. The chamber 2, which is made of considerable size so as to permit of a large number of determinations being made before recharging becomes necessary, which is, as shown, conveniently formed of a piece of metal pipe and has internally threaded ends.

Screwed into one (the upper) end thereof is a cap or casing 3 which forms a body for the valve or cock 4 whereby the flow of gases into and through the chamber 2 is regulated and controlled in operating my improved apparatus. The chamber 2 also has screwed in the threaded opening in the lower end thereof a plug 5 which is adapted to be removed from time to time to permit the insertion of the caustic potash or other reagent used in the vessel or chamber 2. The plug 5 is provided with a screw threaded opening into which a smaller plug 6 is removably secured to enable the interior of the chamber 2 being drained at such intervals as are found necessary or desirable.

The chamber 2 for the reagent is also provided on its interior with the tube 7 (see Fig. 3) which is secured by one end in the passage or inlet opening 8 in the casing 3, and which extends lengthwise within the chamber 2 so as to deliver the entering gases near the lower end of the chamber 2 and cause the entering gases to rise upwardly therein through the reagent a quantity of which is kept within the chamber.

The valve casing 3 is provided with a gas inlet opening 9 which is connected by the tube 10 with a stack flue or stack (not shown), through which the waste gases (of which the carbon dioxid content is to be de-

terminated) are conducted into the atmosphere from a furnace chamber or other place in which the mixture of gases is formed. Another passage 11 in the valve casing 3 is connected by the tube 12 with the inlet opening 13 on the graduated mercury gage 14 or like device whereby the degree of vacuum formed in the chamber 2 is indicated and the percentage of carbon dioxid in the gases therefrom determined. The gage 14 is also provided with a gas outlet opening which is connected by a small tube 15 with the inlet opening of the recording vacuum gage 16 by which the use of which a continuous record is made of variations of fluctuations in the vacuum produced in the chamber 2 during the operation of the apparatus, and the time intervals in which the apparatus is in operation are indicated.

20 An ejector 17 such as a filter pump or equivalent suction producing mechanism is connected to the gas outlet passage 18 in the cock casing 3 in order to increase the velocity of the gases flowing into the chamber 2 and cause a stream of the gases to rapidly pass through the chamber when the cock 4 is turned to the required position as is done at regulated time intervals in the continued operation of the apparatus.

25 The provision of the ejector enables the gases to be caused to flow through the chamber 2 at such a high velocity that the absorption of carbon dioxid (CO_2) during the free flow of the gases will be so small as to be negligible.

30 The gas outlet 18 in the body 3 of the valve connects with one end of a passage or port 19 in the valve body and the passage 19 merges into one end of a radial passage 20 also in the valve body 3. The cock 4 is provided with passages 21 and 22 which are connected together and which coöperate to connect the inlet 9 in the valve body with the passage 8 leading through the tube 7 into the chamber 2. The cock is also provided with connected passages 23 and 24 arranged to extend at right angles to each other and to connect the outlet opening 25 in the valve body 3 alternately with the outlet 18 leading 35 to the ejector 17 and the outlet 11 which leads through the pipe 12 to the mercury gage 14.

35 Preferably, the cock 4 is provided with a stem 26 having a spur pinion 27 keyed or otherwise secured to turn therewith, which meshes with the mutilated gear 28 by which the pinion 27 and cock 4 are intermittently turned. As will be seen by reference to Figs. 2 and 3, the gear 28 is mounted upon a shaft 29 which is secured in bearings formed on the bracket 30 and has a worm wheel 31 secured thereon at an intermediate point in its length. The worm wheel 31 meshes with the worm 32 on the shaft 33, which also is mounted in 40 bearings on the bracket 30 and the shaft 33

is connected in any desired manner with an electric motor or other suitable prime mover (not shown).

The graduated mercury gage 14 has a wire 34 forming a terminal extending into the gage through the upper end thereof, this wire being arranged to be adjusted lengthwise within the glass tube forming part of the gage 14, and the bottom of the gage is connected to one end of a wire 35. The wires 34 and 35 are connected through a battery 36 to the relay 37 and this relay is connected by wires 38 and 39 through a battery 40 with an electric bell 41 so that when the circuit is broken through the wires 34 and 35, as is done by a change in the extent of the vacuum within the gage 14, the relay 37 is actuated so as to complete the circuit through the wires 38 and 39 and ring the bell 41 and in this way sound an alarm or signal audibly indicating the carbon dioxid content of the gases is such as requires attention.

When for any reason it is desired to operate the apparatus to only determine the amount of proportion of carbon dioxid in the mixture of gases at irregular or infrequent intervals, the recording gage and cock turning mechanism and the signaling apparatus may be dispensed with and in such case a handle 42 such as is shown by dotted lines in Figs. 3 and 4 may be provided on the cock 4 by which the cock is turned manually to admit and confine a given volume of gases in the chamber 2 while the vacuum is being formed therein and the carbon dioxid content determined.

The operation of my improved apparatus will now be described: The apparatus is assembled, preferably as shown, and the chamber 2 is supplied with a quantity of caustic potash or other reagent or with a solid absorbent material saturated with a suitable reagent, the material being introduced through the opening in the lower end of the chamber 2 after which the plug or cap 5 is replaced in position. The filter pump 17 forming the type of ejector shown is then started to operate and the motor which drives the shaft 33 is started. When the motor causes the shaft 33 to rotate, the worm 32 thereon turns the worm wheel 31 on the shaft 29 and through this shaft rotates the intermittent gear 28. The intermittent gear is provided at separated intervals on its periphery with a series of sets of teeth 43, 44 and 45.

Assuming the pinion 27 to have 16 teeth and the gear 28 to have a pitch line equivalent to that of a gear with 84 teeth, the gear ratio will be 4 to 1 and the 12 teeth in the set 43 will rotate the pinion 27 and stem 26 through an angle of 270 degrees and, the sets 44 and 45, which have 2 teeth each, will each rotate the pinion 27 and stem through an angle of 45 degrees. The space between

the sets of teeth on the mutilated gear 28 are arranged in such manner that the pinion 27 and stem 26 remain stationary for a time interval after disengagement from each set 5 of teeth 43, 44 and 45.

It is desirable to have one complete cycle of operations in 5 minutes, (a multiple of one hour) so that an interval of 4 minutes will elapse between the time the set of teeth 10 44 becomes disengaged and that at which the set 43 becomes disengaged. A time interval of about 20 seconds will then elapse during which time the teeth of the set 45 engage and disengage the pinion and a time interval 15 of 40 seconds then elapses during which the set 44 engages and disengages the pinion 27. The 4 minute interval then again starts. In this way the pinion 27 is rotated by the set 43 through an angle of 270 degrees 20 and comes to rest. During the next 20 seconds it remains at rest and also is turned by the set 45 through an angle of 45 degrees. In the next 40 seconds it remains stationary and also is further rotated through an angle 25 of 45 degrees. In the next interval of 4 minutes, the pinion is stationary and is also engaged by the set of teeth 43 and moved through an angle of 270 degrees.

After the set 43 disengages from the teeth 30 of the pinion 27, the set of teeth 45 next engages the pinion and during the interval of about 20 seconds, in which the pinion remains stationary and also becomes engaged with and disengaged from the set of teeth 35 45, the cock 4 is in the position shown in Figs. 3, 4 and 5 and during the major portion of this time gases will be drawn, through the action of the ejector 17, into and through the chamber 2. The pinion is 40 then again at rest until the continued rotation of the mutilated gear finally brings the set of teeth 44 into engagement with the pinion and turns the pinion further, through an angle of 45 degrees.

45 During the interval of about 40 seconds required, after the set 45 disengages from the pinion 27, for the set of teeth 44 to engage and disengage the pinion 27, the openings in the cock 4 are all closed and in this time interval absorption of carbon dioxide (CO_2) takes place within the chamber 2. An interval of 4 minutes then elapses during which the passages in the cock are positioned to connect the chamber 2 with the 50 mercury gage 4 and through the gage 14 with the recording vacuum gage 16 and the cock again turned, by the set of teeth 43 through an angle of 288 degrees.

The above described operations which 55 form a complete cycle are then repeated every five minutes so long as the apparatus is maintained in operation and the carbon dioxide content of the gases is determined and recorded at intervals of five minutes.

55 The lead-wire 34 in the mercury gage is

adjusted therein so as to be on a level with any convenient graduation such as the ten per cent. graduation thereon and when in such position make contact with the mercury in the gage when the gage reads "ten 70 per cent." or over. When the mercury engages with the end of the lead-wire 34 the circuit through the wires 34 and 35 is completed which in turn causes closing of the relay circuit so as to hold the relay 37 in 75 disengaged position. In such position the contact on the relay which completes the circuit is held to keep such circuit in open position. Should during the operation of the gage, the mercury column become lower 80 than the ten per cent. graduation or other point at which the movable terminal 34 has been set, the circuit formed by the lead-wires 38 and 39 through the bell 40 is closed so as to cause the bell to ring and in this 85 way sound an alarm.

After the absorption of carbonic dioxid has taken place in the chamber 2 this chamber is connected with the mercury gage 14 and, through the gage 14 and tube 15, with 90 the recording gage 16 so that the amount of vacuum produced in the chamber 2 will be indicated upon the gage 14. The amount of vacuum will also be recorded upon the chart forming part of the recording gage 16 and 95 form a permanent record showing the variations in the amount of vacuum and the time intervals during which a vacuum is formed and the carbon dioxid content of the gases is determined.

100 The advantages of my invention will be apparent to those skilled in the art. By its use an untechnical fireman can readily determine the quantity of carbon dioxid contained in the gases passing from the boiler furnace to the stack and, when properly instructed beforehand, can modify the firing of the furnace in accordance with the result shown by the recording gage.

105 By drawing the gases, to be examined, at high speed through a vessel containing solid caustic potash or other suitable reagent or a solid absorbent material saturated with a suitable reagent, and by temporarily stopping the flow of gases through the container and at the same time connecting the vessel to a vacuum gage or other suitable measuring device the carbon dioxid in the gases is 110 caused to be absorbed and on being absorbed produce a vacuum directly proportional to 115 the percentage of the absorbed gas, that is to say one per cent. = 1/100 of a complete vacuum, and so on, the ultimate result being that one hundred per cent. would produce a reading equal to the barometric 120 height.

125 The velocity of the gases passing through the absorption vessel or container is such that the slight amount of absorption taking place during the time interval in which the 130

4 mixture of gases are permitted to flow freely through the absorption chamber is negligible.

Modifications in the construction and arrangement of the parts may be made without departing from my invention as defined in the appended claims. The means employed in actuating the cock may be other than those shown. The form of the vacuum gage may be varied. The recording gage may be any of the various known types and the means for sounding an alarm may be a whistle instead of the bell as shown.

I claim:

- 15 1. A carbon dioxide gage comprising an absorption chamber containing a reagent to absorb carbon dioxide gas, means for conducting waste gases through said chamber at a velocity substantially preventing absorption of carbon dioxide gas therein, means for interrupting the flow of gases therethrough, and means for indicating the vacuum produced in said chamber when the flow of gases is interrupted and carbon dioxide gas is absorbed to thereby indicate the carbon dioxide content of the gases.
- 20 2. A carbon dioxide gage comprising an absorption chamber containing a reagent to absorb carbon dioxide gas, means for conducting waste gases through said chamber at a velocity substantially preventing absorption of carbon dioxide gas therein, means for interrupting the flow of gases therethrough, and means for indicating the vacuum produced in said chamber when the flow of gases is interrupted and carbon dioxide gas is absorbed to thereby indicate the carbon dioxide content of the gases within the chamber, and means for registering the amount of vacuum produced during the interruptions in the flow of gases.
- 25 3. A carbon dioxide gage comprising an absorption chamber containing a reagent to absorb carbon dioxide gas, means for conducting waste gases through said chamber at a velocity substantially preventing absorption of carbon dioxide gas therein, means for interrupting the flow of gases therethrough, and means for indicating the vacuum produced in said chamber when the flow of gases is interrupted and carbon dioxide gas is absorbed to thereby indicate the carbon dioxide content of the gases, and means for registering the amount of vacuum produced during the interruptions in the flow of gases.
- 30 4. A carbon dioxide gage comprising an absorption chamber containing a reagent to absorb carbon dioxide gas, means for conducting waste gases through said chamber at a velocity substantially preventing absorption of carbon dioxide gas therein, means for interrupting the flow of gases therethrough, and means for indicating the vacuum produced in said chamber when the flow of gases is interrupted and carbon dioxide gas is absorbed to thereby indicate the carbon dioxide content of the gases within the chamber, and means for registering the amount of vacuum produced during the interruptions in the flow of gases.
- 35 5. A carbon dioxide gage comprising an absorption chamber containing a reagent to absorb carbon dioxide gas, means for conducting waste gases through said chamber at a velocity substantially preventing absorption of carbon dioxide gas therein, and means for intermittently interrupting the flow of gases through said chamber to permit absorption of carbon dioxide gas and the formation of a vacuum in said chamber, to thereby determine the percentage of carbon dioxide in said waste gases.
- 40 6. A carbon dioxide gage comprising an absorption chamber containing a reagent to absorb carbon dioxide gas, means for conducting waste gases through said chamber at a velocity substantially preventing absorption of carbon dioxide gas therein, and means for intermittently interrupting the flow of gases through said chamber to permit absorption of carbon dioxide gas and the formation of a vacuum in said chamber, to thereby determine the percentage of carbon dioxide in said waste gases.

95 In testimony whereof, I have hereunto set my hand.

EDWARD A. CUNNINGHAM.
